UNITED STATES PATENT OFFICE.

LAZARD KAHN, OF HAMILTON, OHIO.

DESIGN FOR A STOVE DOOR OR PANEL.

SPECIFICATION forming part of Design No. 27,111, dated May 25, 1897.

Application filed April 10, 1897. Serial No. 631,638. Term of patent 14 years.

To all whom it may concern:

Be it known that I, LAZARD KAHN, a citizen of the United States, residing at Hamilton, Butler county, Ohio, have invented and produced a new and original Design for a Stove Door or Panel, of which the following is a specification, reference being had to the accompanying drawings, showing the same.

Figure 1 is a front elevation of a stove door or panel, showing my design; and Fig. 2 is a plan of the same.

The leading feature of my design consists of a door or panel having a circular outline and having projecting from its face a closed

front circular register provided with a projecting handle. 15

A is the door or panel, which is circular in outline, B being the closed front circular register, projecting outwardly from the face of the door or panel, and C being the projecting handle on the register. 20

What I claim is—

The design for a stove door or panel, substantially as shown and described.

LAZARD KAHN.
